UNITED STATES PATENT OFFICE.

WILLIAM R. STUCK, OF OAKLAND, CALIFORNIA.

FLOWER-HOLDER.

1,196,312.

Specification of Letters Patent. Patented Aug. 29, 1916.

Application filed August 23, 1915. Serial No. 46,806.

To all whom it may concern:

Be it known that I, WILLIAM R. STUCK, a citizen of the United States, and a resident of the city of Oakland, county of 5 Alameda, State of California, have invented a certain new and useful Flower-Holder, of which the following is a specification.

The invention relates to a stand for holding the stems of a bouquet.

10 An object of the invention is to provide a holder having improved means for the dressing of the bouquet.

Another object of the invention is to provide a holder having means for supporting 15 the flower stems at points intermediate their ends, so that long stem flowers may be properly arranged.

The invention possesses other advantageous features, which, with the foregoing, will 20 be set forth at length in the following description, where I shall fully explain that preferred form of my invention which is illustrated in the drawings accompanying and forming part of the specification. The 25 novelty of the invention will be included in the claims succeeding said description. From this it is apparent that I do not limit myself to the showing made by the said drawings and description, as I may adopt 30 other variations within the scope of my invention as set forth in the said claims.

Referring to the drawings: Figure 1 is a perspective view of the holder of my invention showing a bouquet arranged 35 therein. Fig. 2 is a perspective view of a modified form of the holder, portions being broken away to show the interior and to reduce the size of the figure. Fig. 3 is a fragmentary vertical section of the form 40 of holder illustrated in Fig. 2. Fig. 4 is a view of the supporting rod, a portion being broken away to reduce the size of the figure. Fig. 5 is a top view of another modification of my invention when fashioned to 45 resemble a turtle. Fig. 6 is a vertical section taken on the line 6—6 of Fig. 5.

The flower holder of my invention which is particularly adapted to be used in connection with shallow bowls, vases or dishes, 50 consists of a pair of foraminous plates 2 and 3 spaced apart vertically and secured together by means of a base ring 4 in which the edge of the lower plate 3 and the edge of the down-turned wall 5 of the upper 55 plate 2 are held. The base ring is of sufficient weight to resist the overturning effect

of a tall bouquet of flowers arranged in the holder.

Preferably, the two plates consist of wire netting or screen, but they may be formed 60 from sheet metal. In either case they are best secured together by holding in proper relative position and casting the base ring about their edges so that the whole forms a rigid structure. The bottom edge 6 of 65 the side wall 5 may be curved so that it is held more firmly in the metal of the ring. The lower plate 3 is held in the ring near its upper edge 7 so that there is a space left 70 below the plate. Heretofore, flower holders of this nature have been formed with vertical passages extending completely therethrough, the passages being entirely bounded by walls, forming, as it were, a 75 plurality of vertical wells into which the flower stems were inserted. Such prior construction, therefore, offered very limited opportunity for dressing a bouquet, since the flower stems could only be inserted in the wells and the person dressing the bouquet 80 was constrained to allow them to virtually adjust themselves. With the holder of my invention, however, in which two foraminous plates spaced apart vertically are employed, the flower stems may be inserted at 85 any desired angle, either vertically or otherwise, and the bouquet may be spread or bunched as desired. This holder, therefore, provides unlimited opportunity for dressing 90 bouquets in any artistic and attractive shapes and the formation of the bouquet is under the control of the person dressing it.

For flowers having thin stems, a holder having small openings in the plates may be used, while for thick stem flowers a holder 95 having larger openings is used. Preferably, the upper foraminous plate has larger apertures than the lower plate, such an arrangement producing closer spacing of the apertures in the lower plate, which permits of a 100 greater number of angles at which the stems may be placed, but both plates may be provided with the same sized apertures when desired. In Fig. 1 I have shown some of the flower stems inserted vertically and some inserted at an angle to produce an even distribution of the bouquet.

Many flowers, such as carnations, have long slender stems which are not of sufficient rigidity to hold the flowers without 110 bending and drooping to such an extent as to mar the appearance of the bouquet.

When such flowers are to be arranged in a bouquet, I provide means for supporting the stems intermediate their ends and preferably adjacent their upper ends, so that they may be properly held. Such means consists of a rod 12 formed at one end to fit into the apertures in the upper and lower foraminous plates so that it is held upright when placed therein. Attached in any suitable manner to the upper end 13 of the rod 12 are a plurality of fine tie wires 14. When the bouquet is one having long slender stems, the rod 12 is pushed down into the foraminous plates and the wires 14 looped about the stems as shown in Fig. 1 so that each stem is held in proper relation to the others and stability is given to the whole. The rod 12 is preferably of the twisted light wire construction shown in Fig. 4 and is preferably painted green so that it is not noticeable when placed in the midst of the bouquet. If desired, the flower holder may be made in the shape of a turtle as seen in Fig. 5. In this case the shell of the turtle 16 constitutes the upper foraminous plate. A piece of netting 17 is sprung into the groove 18 left in the lower inside edge of the "shell" and this netting constitutes the lower fo-

raminous plate. If it is desired to further secure the plate in the "shell", lead may be poured into the groove about the edges of the plate. The weight of the lead is also useful in promoting the stability of the flower holder.

I claim:

1. In a flower holder, a base ring, a foraminous plate having its edge embedded in said ring and a second foraminous plate spaced above the first named plate and with downturned edges embedded in said base ring.
2. In a flower holder, a pair of foraminous plates attached together in spaced relation and adapted to hold the lower portion of flower stems, an upwardly extending rod arranged in the openings in said plates, and fine tie wires attached to the upper end of said rod and adapted to secure the upper portion of the stems.

In testimony whereof, I have hereunto set my hand at San Francisco, California, this 17th day of August 1915.

WILLIAM R. STUCK.

In presence of—
H. G. PROST.
